(57) **CLAIM**

The ornamental design for a frame structure for art work, as shown and described.

DESCRIPTION

FIG. 1 is a front perspective view of a frame structure for art work,

FIG. 2 is a rear perspective view of the frame structure shown in FIG. 1,

FIG. 3 is a front view of the frame structure,

FIG. 4 is a rear view of the frame structure,

FIG. 5 is a top view of the frame structure,

FIG. 6 is a bottom view of the frame structure,

FIG. 7 is a side view of the frame structure from one side,

FIG. 8 is a side view of the frame structure from the other side,

FIG. 9 is a front perspective view of a first modification of the frame structure for art work shown in FIG. 1,

FIG. 10 is a rear perspective view of the first modification of the frame structure,

FIG. 11 is a front view of the first modification of the frame structure,

FIG. 12 is a rear view of the first modification of the frame structure,

FIG. 13 is a top view of the first modification of the frame structure,

FIG. 14 is a bottom view of the first modification of the frame structure,

FIG. 15 is a side view of the first modification of the frame structure, from one side,

FIG. 16 is a side view of the first modification of the frame structure, from the other side,

FIG. 17 is a front perspective view of a second modification of the frame structure for art work as shown in FIG. 1,

FIG. 18 is a rear perspective view of the second modification of the frame structure,

FIG. 19 is a front view of the second modification of the frame structure,

FIG. 20 is a rear view of the second modification of the frame structure,

FIG. 21 is a top view of the second modification of the frame structure,

FIG. 22 is a bottom view of the second modification of the frame structure,

FIG. 23 is a side view of the second modification of the frame structure from one side,

FIG. 24 is a side view of the second modification of the frame structure from the other side,

FIG. 25 is a front perspective view of a third modification of the frame structure for art work as shown in FIG. 1,

FIG. 26 is a rear perspective view of the third modification of the frame structure,

FIG. 27 is a front view of the third modification of the frame structure,

FIG. 28 is a rear view of the third modification of the frame structure,

FIG. 29 is a top view of the third modification of the frame structure,

FIG. 30 is a bottom view of the third modification of the frame structure,

FIG. 31 is a side view of the third modification of the frame structure from one side, and,

FIG. 32 is a side view of the third modification of the frame structure from the other side.
